UNITED STATES PATENT OFFICE.

HARRISON L. STALEY, OF MARTINSVILLE, INDIANA, ASSIGNOR TO THE ROTO COMPANY, OF HARTFORD, CONNECTICUT, A CORPORATION OF CONNECTICUT.

CUTTER HEAD FOR TUBE CLEANERS.

Application filed January 2, 1923. Serial No. 610,112.

To all whom it may concern:

Be it known that I, HARRISON L. STALEY, a citizen of the United States, residing at Martinsville, in the county of Morgan and State of Indiana, have invented a new and useful Improvement in Cutter Heads for Tube Cleaners, of which the following is a specification.

This invention relates to the type of motor rotated cutter heads for cleaning deposit from the interiors of the tubes of boilers, condensers, evaporators and the like apparatus, which have cutters mounted on the ends of arms that are pivoted to the motor rotated body by transversely extending pivots in such manner that the cutters oscillate radially due to centrifugal action when rotated in the tubes for engaging and dislodging the deposit therefrom.

10 The cutters of devices of this character dull and break during use and from time to time it is necessary to remove the old cutters and replace them with new cutters. It is also sometimes necessary to renew the arms which carry the cutters. Where the deposit is hard such substitution is required to be made quite frequently. In some types of apparatus the tubes are made of soft metal and in cleaning such tubes it is essential that they be protected from being injured by the cutters.

15

The object of this invention is to provide a construction whereby the head may be made and assembled by the manufacturers very cheaply, and worn or broken cutters and arms may be easily removed and new parts quickly substituted by the user, which construction also allows the extent of expansion or outward throw of the cutters to be readily predetermined in a very simple manner so that the cutters may be adjusted to the diameter of the tubes and the character of the tubes with which they are to be used.

20 In the accompanying drawings Figure 1 shows a side view of a cutter head constructed according to this invention. Fig. 2 shows a central section of the head. Fig. 3 shows an end view of the head. Fig. 4 shows a transverse section on the plane indicated by the dotted line 4—4 on Fig. 1.

The body 5, or spider as it is commonly termed, of the head illustrated has a threaded stem 6 by means of which it may be fastened to the driving motor. Extending lon-

gitudinally in the sides of the body are four grooves 7 and pivoted in these grooves are four arms 8. The arm pivots 9 which extend transversely of the axis of the head through the walls of the body at the sides 60 of the grooves are larger at their ends than at the center and are fitted so they may be easily driven into or out of place. Each arm has a longitudinal bore for receiving the headed bolt 10 which carries the cutter 65 11. A pin 12 is driven through each arm and each cutter bolt to hold the cutter bolt in place. The inner end of each cutter bolt is forked and the bolt is of such length that when in place the fork straddles the portion 70 of the arm pivot that is reduced in diameter. The pivots are first thrust through the arms so as to retain them in position. Then cutter bolts with the cutters rotatably mounted on them are thrust into the arms 75 and the pins driven through the arms and bolts. With the bolts fastened in this manner it is impossible for the arm pivots to slip out of place, they being held from longitudinal movement by the engagement 80 with their reduced sections of the forked ends of the bolts.

Each arm is extended beyond its pivot and the inner side of this end is cut away, as at 13, so that the end of the arm bearing the cutter may swing outward. A ring 14 is slipped on the stem of the body. This ring is of such diameter that it will limit the outward swing of the cutters. Before this ring is placed in position the arms can swing open sufficiently to allow the pins to be driven through the arms and the cutter bolts. After the parts have been assembled with the pivots that retain the arms, held in place by the bolts which carry the cutters, and the bolts secured by the pins, the ring is slipped upon the stem. When the ring is in place it is engaged by the extensions on the ends of the arms in such manner that the arms cannot swing out far 100 enough to carry the pins which hold the bolts beyond the edges of the walls of the grooves in which the arms are pivoted, that is, after the ring has been placed on the stem the bolt pins are held from moving 105 either way out of place by the side walls of the grooves. By using rings of different diameters the outward throw of the cutters may be regulated, that is, if it is desired to have the cutters swing out a relatively great 110

2
distance the ring may be small in diameter, while if it is desired to prevent the cutters from swinging out so that they will engage the inner walls of the tubes a larger ring 5 may be placed on the stem.

In order to substitute new cutters the head is screwed off from the motor sufficiently to allow the ring to be drawn back beyond the extension of the arms. Then the 10 arms can be swung out far enough to permit the pins to be driven out and the bolts removed. After new cutters have been put in and the bolts returned and pinned the head may be again screwed onto the motor so as to crowd the ring forward and prevent the 15 arms from opening sufficiently far to allow the pins to become displaced. If a new arm is to be substituted, after the pins have been driven out and the bolts removed the arm 20 pivots may be easily pushed out.

This construction is very simple to manufacture and easy to assemble and manipulate for the arms are retained by the pivots which are held by the cutter bolts that are 25 fastened by the pins which in turn are prevented from slipping out by the side walls of the slots containing the arms that are prevented from opening far enough to allow the pins to slip out by the ring on the stem.

30 The invention claimed is:

1. A tube cleaner cutter head comprising a body having longitudinally extending grooves, arms pivotally held in said grooves, cutter bolts extending into said arms and 35 adapted to engage and hold the arm pivots in position, pins extending through the arms and bolts for holding the latter in position, and adjustable means on the head for engaging and preventing the arms from 40 swinging out sufficiently far to carry the

bolt pins beyond the walls of the grooves supporting the arms.

2. A tube cleaner cutter head comprising a body having longitudinally extending grooves, arms pivotally held in said grooves, 45 cutter bolts extending into said arms and adapted to engage and hold the arm pivots in position, pins extending through the arms and bolts for holding the latter in position and a loose ring on the head for engaging the 50 ends of the arms and preventing them from swinging out sufficiently far to carry the pins beyond the walls of the grooves supporting the arms.

3. A tube cleaner cutter head comprising 55 a body, arms pivoted to the body, cutter bolts extending into said arms and adapted to engage and hold the arm pivots in position, and pins extending through the arms and bolts for holding the latter in place. 60

4. A tube cleaner cutter head comprising a body, arms pivoted to the body, cutter bolts extending into said arms and adapted to engage and hold the arm pivots in position, means for holding the bolts in place, 65 and a ring on the head for engaging the ends of the arms and limiting their outward swing.

5. A tube cleaner cutter head comprising 70 a body having longitudinally extending grooves, arms pivotally held in said grooves, cutter bolts extending into said arms, pins extending through the arms and bolts for holding the latter in position, said pins being held from removal by the walls of the 75 grooves supporting the arms, and removable means for limiting the outward swing of the arms.

HARRISON L. STALEY.
